UNITED STATES PATENT OFFICE.

LAWRENCE H. MORSE, OF CLEVELAND, OHIO, ASSIGNOR TO THE AMERICAN MULTIGRAPH COMPANY, OF CLEVELAND, OHIO, A CORPORATION OF OHIO.

PAPER-FEEDING MECHANISM.

Application filed December 22, 1924. Serial No. 757,352.

This invention relates to an addressing machine of the type wherein plates are fed one after another from a stack and passed between a pair of platens which effect the printing impression upon paper, after which the paper and plates are discharged into respective receptacles. Ink for the impression is provided in a suitable manner, as for instance by means of an inking ribbon interposed between the plate and the paper.

One of the objects of the present invention is to provide a simple and efficient mechanism for feeding sheets of paper, cards, envelopes, bulletins, booklets, etc., one after another to the impressing region. This paper feeding mechanism (receiving the paper units one after another from a manual or automatic feed as desired) automatically controls the starting of the feed and there-20 after progresses the paper unit until the impression is effected and the printed unit delivered. Suitable adjustments enable the placing of the imprint on the sheet in any desired location.

Another feature of the invention comprises an effective mechanism for alternately moving one of the platens from a normally inactive position to its active position and then returning it following the printing impression, the result being that this platen is only active at or about the time of the impression, and smudging of the platen by inadvertently inking it is prevented.

Another feature of the invention relates to mechanism enabling selective operation of the machine; that is to say, printing from only certain address plates, the other plates being run through the machine idly. This mechanism is combined with the mechanism above mentioned for periodically moving the platen to active and idle positions, and results in the platen remaining inactive except when plates of the selected character are present. More specifically, I control this selection by tabs on the plates differently positioned according to the classification of the plate, the tab in the selected location operating a suitable mechanism to cause the normally idle platen to come to active position.

The characteristics mentioned are herein-after more fully explained in connection

with the description of a preferred embodiment of my invention shown in the drawings thereof.

In the drawings, Fig. 1 is a side elevation of my machine substantially complete, but with certain portions, as the paper table and the sheet receiving tray, omitted and the upper portion of the stack, part of the drawer and frame broken away; Fig. 2 is a plan of the machine, the paper table and driving crank being broken away; Fig. 3 is a vertical longitudinal section in a plane parallel with Fig. 1, certain parts being broken away; Fig. 4 is a horizontal section through the magazine; Fig. 5 is a vertical section taken on line 5—5 of Fig. 4, but on a larger scale, showing the selective operation of the address plate tabs; Fig. 6 is a perspective of the address plate tab; Fig. 7 is a horizontal cross-section on the line 7—7 on Figs. 3 and 5; Fig. 8 is a side elevation of the driving mechanism, and certain controlling cams, this view looking from the opposite direction to Fig. 1; Fig. 9 is a vertical section through the main shafts, the plan of the section being indicated by the line 9—9 in Fig. 1; Fig. 10 is a vertical section longitudinally of the machine illustrating the mechanism for controlling the activity or inactivity of the platen, the plane of this section being indicated by the line 10—10 of Fig. 2; Fig. 11 is a view of certain of the parts shown in Fig. 10 in another position; Fig. 12 is a plan of the ribbon-carrying frame and certain of its coating parts; Fig. 13 is a perspective of an address plate and tab which may be used in the particular machine shown.

My invention is shown in the drawings as adapted for embodiment in an addressing machine of the type shown in application No. 745,902 filed October 25, 1924, by Clifton Chisholm. Reference is made to that application for claims on such features of the complete machine shown as the plate magazine, the restacking magazine and the ribbon carrying mechanism. While my invention is not confined to use with that particular machine, it will be convenient to describe first the general characteristics of such complete machine.

The frame of the machine consists essen-

tially of a horizontal bed 10, having a longitudinal depressed portion 11, suitable supporting legs 12, and various upright brackets, the magazine for the stack of plates 5 comprising an upright structure at the rear of the machine, which is the left-hand end as shown in Figs. 1, 2 and 3. The magazine frame consists briefly of a bracket 20 hinged on a shaft 21 mounted in the bed. 10 This bracket carries a sheet metal back 22 of the magazine and also a pair of horizontally projecting feet 23 adapted to engage the bottommost plate and support the stack. The front and sides of the magazine comprise 15 L-shaped plates 25 carried on yokes 26 pivoted at 27 and having inwardly-projecting slidably-connected arms 28. Suitable means, not shown, are provided for swinging the yokes apart to separate the plates 25 and 20 open the front of the magazine for installation of the address plates.

While the machine may be adapted to carry any suitable address plate, it may be mentioned that the particular plate shown, 25 designated A, in Figs. 4 and 13, comprises a sheet metal body having on its upper surface rows of raised buttons a , with overhanging edges, these buttons being pressed from the plate material and carried by upwardly extending corrugations a^1 of the plate. The edges of the buttons are free from the plate and thus are adapted to be underhung by the inwardly flanged edges of suitably embossed strips B mounted thereon and carrying the printing characters. 30 The ends of the plate are bent into hollow ribs a^2 providing suitable stiffness.

The address plates are fed one after another from the bottom of the magazine forwardly to their active position by a pair of sprocket chains 50, each of which has a horizontal upper reach extending forwardly above the depressed portion 11 of the bed, the two chains lying in two vertical planes 40 as illustrated in Figs. 3 and 7. The two chains at their forward ends are shown as looped around a pair of sprockets 51 pinned on a drive shaft 52, rotatably mounted in the bed. At the rear these chains pass 45 around sprockets 54 mounted in a yoke 56 adjustably supported by the rear end of the frame.

Certain links of the chains 50 have upstanding lugs 60 adapted to engage the end ribs a^2 of the bottommost address plates A 55 in the magazine, and thereby draw such plate forwardly as the chains travel. In the embodiment shown, there are two of these lugs on each chain 50, and the machine is designed to feed the chains one-half their 60 length at each cycle of operation.

Loosely journaled on the shaft 52 between the wheels 51, is the supporting platen 70 for the address plate. This platen has a 65 segmental portion 71 designed to support

the plate during printing operation. The segmental portion may have radial ribs 74 adapted to occupy grooves a^1 formed in the underside of the address plate A. A suitable lip 75 at the forward edge of the platen 70 forms a stop for the plate at the beginning of the printing impression.

Directly above the supporting platen 70 is the arcuate impression platen 81 carried on a rotatable drum 82 mounted on and driven by the main shaft 80. These members, however, constitute part of my paper feed mechanism and will be hereinafter described. On the shaft 80 is an operating handle 87. Suitable gears 88 and 89 connect 80 the shafts 80 and 52.

It results from the above described mechanism, that when the crank is rotated in the proper direction, the gear and sprocket chains carry the bottommost plate in the magazine forwardly into position between the two platens so that it may impress paper traveling forwardly with the plate at this point. I prefer to provide the ink for the impression by means of a ribbon C, which 90 overlies the plate and underlies the paper.

In the machine shown, the ribbon is carried on a pair of spools mounted on a reciprocating frame. This frame is best shown in Figs. 1, 2, 3 and 12 and comprises a pair of parallel bars 110, a cross bar 112 rigidly connecting them at their forward ends and a cross bar 113 to connect them at their rear ends. The latter cross member is provided with upstanding ears 115 carrying the rear ribbon spool 120. The forward cross bar 112 has downwardly extending ears 116 carrying the forward spool 121. The ribbon extends intermediately in substantially the same plane as the bars 110 but 105 between them. The bars 110 are guided by flanged rollers 118 carried by the stationary frame.

The ribbon carrying frame described is reciprocated consequent upon the rotation 110 of the main shaft 80. To effect this, a cam groove 130 may be provided on the inner face of the main gear 88. This groove receives a roller 131 on the arm 132 pivoted at its upper end to the right hand side of the frame bracket 15 and at its lower end engaging the reciprocating rod 135 slidably mounted in this bracket and connected to the reciprocating ribbon frame as by an extension of the cross bar 112. The cam groove 130 is so formed that the ribbon frame moves forwardly with the plate during impression at the same speed as the plate, but following the printing impression, the frame returns to its rearward position.

To feed the ribbon step by step automatically as it is reciprocated, I prefer to place a ratchet wheel as 140, 141, on each spool, one or the other of which wheels coacts with 130

a corresponding pawl 142 or 143 carried on a bar 145 intermediately pivoted as at 144 in Fig. 1. When the bar is in the position shown in this figure, the pawl 143 engages 5 the ratchet wheel 141 and rotates it the distance of one ratchet tooth as the reciprocating frame is coming into its rearmost position. If, however, the bar 145 were swung slightly so as to elevate the rear end, the 10 pawl 142 would engage the ratchet wheel 140 while the pawl 143 would clear the ratchet wheel 141.

Following the printing impression the plate is delivered to the receiving drawer. 15 A suitable drawer is shown at D in Fig. 3 and supported in a slightly inclined position beneath the bed of the machine. In front of the supporting platen 70 is an inclined and curved support 150 down which 20 the used plate may be slid. In such movement the forward edge of the plate strikes against the face of a packer 152 pivoted at 153 and depending into the drawer. The plate then slides downwardly into the drawer 25 as indicated at A. The swinging packer 152 is connected by an eccentric strap 154 with an eccentric 155 on the shaft 52, the result being that the discharged plates are packed one after the other into the drawer.

30 The machine so far specifically described is not itself comprised within my invention but is the invention of Clifton Chisholm as already mentioned. I prefer however to provide a mechanism I have devised for 35 swinging the supporting platen in place of that shown in the Chisholm application.

To rock the supporting platen 70 into active position and cause its surface to travel 40 forwardly at the same speed with the reciprocating ribbon frame, I mount on this reciprocating frame a rack 157 which meshes with a toothed sector 158 connected by a link 159 with the rocking member 70. The proper proportioning of the lever arms of 45 the two rocking members 158 and 70, substantially as shown in Fig. 3, causes the arcuate surface of the supporting platen to move at a speed almost exactly the same as the straight movement of the inking ribbon.

50 Any slight inaccuracy is compensated for by looseness in the pivots of links 159, since the supporting platen is in effect geared with the plate by reason of the ribs 74 on the platen meshing with the grooves a^1 in the plate, such engagement taking care of 55 properly moving the platen while the looseness described allows it.

I will now describe my paper feeding mechanism which is adapted to take sheets, envelopes, cards, bulletins or booklets, one after the other from an elevated table and carry them around into a position to coact with the supporting platen, address plate and inking ribbon of an addressing machine,

and in the embodiment may well cooperate 65 with such parts of the Chisholm machine.

The paper feeding drum 82 heretofore mentioned best shown in Figs. 3 and 9, is conveniently made as a complete metal drum carrying on its surface yielding bands 160 70 and 161, of rubber or other suitable material. This drum carries also the arcuate yielding platen 81. The endmost rubber bands 160 are completely annular; the intermediate band 161 is incomplete having 75 its ends terminating adjacent the edges of the platen.

The drum described is mounted on an eccentric sleeve 165 which receives and bears on the shaft 80 and is also journaled in the 80 left hand side of the frame bracket 15. The drum is connected by a shiftable coupling to the shaft 80, so that it may be rotated thereby, irrespective of the position of the eccentric sleeve. For this purpose I have 85 shown an Oldham coupling comprising a collar 166 pinned to the shaft 80, and a ring 167 having a pair of diametric lugs engaging a diametric groove in the collar and another pair of lugs located 90° from those 90 first mentioned and engaging a groove in the drum.

To turn the eccentric sleeve to bring the drum to and from active position, I provide the following mechanisms. In the left hand 95 end portion of the eccentric (Fig. 9), I secure a stub shaft 170; loose on this shaft I place a lever 171, and I connect this lever adjustably to an arm 172 rigid on the shaft. As shown, the arm 172 has an arcuate slot 100 173 through which a screw 174 passes into the lever 171. The lower portion of the lever 171 is connected by links 175 with a rock arm 176 on a shaft 177, mounted in the frame member 15. Rigid on this shaft 177 is 105 a rocker 180 carrying a roller 181 adapted to coact with a cam 182 rigidly secured to the shaft 80, Figs. 9, 10 and 11. A spring 184 tends to keep the roller in contact with the cam and to turn the eccentric in the direction 110 110 to lower the paper drum 82, so that its platen 81 may coact with the supporting platen 70 and the interposed address plate.

In what may be called normal operation, the lowering of the platen takes place once 115 each revolution as the portion of the cam 182 of shortest radius comes into action with the roller 181. Such action takes place just as the platen 81 has come into position for coaction with the plate. However, I provide mechanism hereafter described for holding the rocker in its idle position, that is, with the platen non-effective for successive rotations of the drum, and this will be 120 described in connection with the plate-selecting mechanism.

Coacting with the elastic rings 160 and 161 on the upper feeding drum are belts 190,

which as shown in Fig. 3 lie for a considerable distance in contact with the rubber rings. Each of these belts is carried by three rollers 191, 192 and 193. The rollers 191 are mounted a short distance back from the drum on a shaft journaled in the frame members 15 and 16. The rollers 192 are each mounted in a yoke-shaped lever 195 loose on a rod 197, and have a tendency to swing 10 toward the rear by reason of springs 196 connected with the upper ends of these levers. The roller 193 is mounted on a shaft 199 carried by the arms 200 and 201 of the rocking frame or yoke 202, which is mounted 15 on the shaft 203 above the paper drum. In operation, the yoke described is rigid with the shaft 203, but it is adjustable thereon by means of the yoke being freely mounted on the shaft and connected by a screw 205 20 with a collar 206 tight on the shaft.

On the shaft 203 there is rigidly secured also an arm 207 carrying an adjustable screw 208. This screw bears at its lower end against a rock arm 210 on a shaft 211 25 which carries a number of arms 212. Each of these arms is provided at its rear end with an up-turned stop finger 213. Between these arms are rollers 214 in a region forward of the stop fingers and directly beneath the belt rollers 193. The paper table 220, broken away in the drawings, extends over the arms 212 to a point adjacent the drum 82 and is provided with openings 30 through which the stop fingers 213 and rollers 214 may project above the top of the table.

The paper may be carried in a suitable pile on the extending portion of the paper table 220 and fed manually or otherwise as 40 desired, one at a time toward the rear, until stopped by the advancing edge engaging the raised stop fingers 213. At the proper time in the cycle of operation mechanism to be described rocks the yoke 200 to lower the 45 rollers 193, bringing the traveling belts 190 into engagement with the top surface of the stopped sheet. At the same time, the adjustable screw 208 rocks downwardly the arms carrying the stop fingers so that they 50 are withdrawn from the path of the sheet, and, simultaneously, the sheet is gripped between the belts and the rollers 214 and is thus fed rearwardly and gripped between the belts and the drum. The rotation of the 55 drum then carries the sheets around with it so that it passes between the drum and the supporting platen, and, clinging to the drum at its forward edge, passes above the discharge guide plate 230 and between the drum 60 and ejector rollers 231, carried by rock arms 232 mounted on a cross-shaft 233 and spring pressed toward the drum. The sheet thus emerges through the horizontal discharge slot 235 (Fig. 3) into a suitable receptacle 65 (not shown).

It is to be understood that at the proper time in the described progress of the sheet, the eccentric sleeve 165 is turned, by the mechanism heretofore described, to bring the platen 80 into coaction with the address 70 plate and supporting platen 70 to effect the impression on the paper.

To determine the location of the address printed on the sheet, I vary the time when the sheet is originally gripped with reference to the rotation of the drum. This is effected by controlling the rocking of the yoke 202 by a cam movably mounted on the gear 88, rotating with the drum. This cam is shown in Figs. 8 and 9 as comprising an annular member 240 having an enlarged portion 241. A cam is adjustably clamped on the gear by screws 243. This cam acts on a roller 245 on a lever 246, secured to the shaft 203, carrying the rocking yoke 202. 80 The roller 245 is maintained in contact with the drum by springs 247 acting on arms 248 forming a portion of the yoke 202. From this it results that at the proper time, as determined by the location of the cam 240 on the gear 88, the paper is gripped and fed with the drum so that the proper region of the paper is across the arcuate platen 81 and thus comes between the printing plate and is impressed. Springs 247 may have 90 their tension adjusted by changing the position of their anchorage arms 249 on their supporting rod 250. These same springs maintain the contact between the adjusting screw 205 and the arm 206. 100

Adjustment is made for different thicknesses of paper from tissue paper to small booklets by turning the screw 205 so that the sheet will be gripped with the proper firmness. The screw 208 may also be turned 105 to raise or lower the stop finger according to the thickness of the material fed. Engagement of the paper by the belts is caused by the springs 247 whenever the depressed portion of the cam 240 allows it. The positive action of the cam by reason of the raised portion 241 serves to separate the belts and rollers 214 and cause the raising of the stop fingers 213 into the position shown in Fig. 3. 115

The machine so far described is complete to take plates from a stack and feed them forwardly together with the inking ribbon and to receive the paper supplied to the stop fingers and feed it about the paper drum to effect the printing impression on the paper in the desired region thereof, and thereafter deliver the paper to its receptacle and discharge the used plate to the receiving drawer. My invention however, contemplates the further feature of mechanism to enable any plates desired to pass idly through the machine, the paper being fed only for selected plates, whereby when the stack of address plates is run through the machine, only those of a certain group effect an impression, the 125 130 135

remainder being simply idle and discharged to the receiving drawer. The mechanism enabling this selection, irrespective of the position of the plates in the stack will now 5 be described.

The selection of the desired group of plates is controlled by suitable tabs adjustably positioned on the plate. In Figs. 4, 5, and 6, I have shown certain tabs E made in accordance with patent 1,500,438, granted July 8th, 1924, to Clifton Chisholm, each tab comprising a doubled spring metal member having a short arm e with a raised transverse portion e' adapted to overlie an edge rib 15 a³ on the plate. On the underside of the plate, the tab has a longer arm e² having an opening e³ adapted to receive downward projections a⁴ on the plate. There are a number of these projections and the tab may be 20 located with reference to any one of them, its location determining the group to which that plate belongs. These tabs, by mechanism about to be described, operate to control the mechanism which lowers the drum 25 so that the drum is lowered only when the bottommost plate is one having its tab in the selected location.

The mechanism by which the selection is effected is best shown in Figs. 3 to 8 inclusive. Directly beneath the back portion of the magazine, in position to be engaged by correspondingly positioned tabs E is a row of vertical pins 260. Each pin engages at its lower end with a blade 261 constituting a 35 narrow lever loosely journaled on a supporting rod 262. Any or all of these blades are retained in an idle horizontal position beneath the depressed portion 11 of the bed by means of individual spring fingers 263 on a 40 comb carried on the underside of the bed. If all of these blades are in this horizontal position, the selecting mechanism is idle and all of the plates are printed from irrespective of the position of the tabs E thereon.

45 When it is desired to print only selected plates, the blade 261 corresponding to the position of the tabs of the desired group is lowered so that it comes into the position shown in broken lines in Fig. 5 with the nose of the blade engaging underside of the magazine feet 23 and with the corresponding pin 260 elevated. Such movement of any desired blade is effected in any suitable manner, a simple means being to push a rod down 50 through one of the openings 265 in the bed plate to push the blade downwardly free from its retaining spring. When the blade is in the lowermost position described it stands in front of a rocking member 270 having a 55 universal bar 271 at its rear edge extending in position to engage any lowered blade. This rocker is secured to a rock shaft 273 on one end of which is a rock arm 274 connected by a link 275 with a rearward extension of 60 the arm 246, which is rigid on the shaft 203

carrying the yoke 202 controlling the belts.

Accordingly, so long as the selected and depressed blade 261 remains in its lowermost position no paper is fed for the successive rotations of the drum, but the plates are 70 transferred idly one after another from the bottom of the stack into the receiving drawer D. When, however, the bottommost plate of the stack has its tab E in the position corresponding to the depressed blade 261, such 75 tab will engage the raised pin 260 and thus swing the inclined blade 261 into the position shown in full lines in Fig. 5 so that its forward end clears the universal abutment 271 on the rocker 270. This enables the drum to 80 operate as usual, to feed the paper and move downward to effect the printing impression. A suitable weight placed on top of the stack of plates in the magazine insures even the last plate effecting this operation should it 85 carry the selected tab.

Loosely mounted on the shaft 203 but held by a spring 290 to the arm 207 is an arm 291 adapted to coact with a shoulder 292 on the upper arm of the rocker 180 which controls the turning of the platen. When the cam 182 has moved this rocker into its lowermost position (Fig. 11) to raise the platen, the arm 190 under the influence of the spring 290 comes over the shoulder 292 to lock the 90 95 rocker in this position. Such lock is released for every rotation of the drum which prints. When the arm 207 is rocked down to release the stop fingers 213 an adjustable screw 295 on this arm at the same time swings the arm 100 291 to idle position and releases the rocker 180. When any depressed selector blade 251 prevents the rocking of the yoke 202 as described so that no paper is fed, this likewise prevents the release of the lock 291 so that 105 the eccentric sleeve 165 remains with the paper drum elevated and neither is this drum lowered nor the paper gripped until the selected blade is moved to release the universal abutment 271.

To increase the number of possible selections with one tab on a plate, I may narrow the doubled end of the tab as shown in broken lines in Fig. 4, allowing the pins 260 to be placed more closely together. Fig. 4 115 shows tabs of three different forms, the tab E overhanging two pins, tab E¹ overhanging the left hand one of the pins which a full-width tab would engage, and the tab E² the right hand one of such two pins. By 120 employing these three characters of tabs, I am therefore able to cause three different selections for each tab position of the plate. It will be seen however, that the number of 125 selections may be increased many fold by employing a plurality of tabs on a plate, since my selecting mechanism may operate equally well with combinations of pins and blades as with a single pin and blade active. Inasmuch as any one blade in the lowermost 130

position prevents the operation of the machine, if three blades for instance are lowered it is obvious that the raising of any one or two will not enable the operation of the machine, but that suitably placed tabs may insure the raising of the three, to allow the operation.

It will be seen that the selecting mechanism is very simple. It is only necessary to 10 push down the blade or blades which correspond in position to the desired tab or tabs, and thereafter the operation is automatic to print from such selected plates only. To change the selection, any depressed blade is 15 raised to its normal idle position and a new blade depressed. To raise the blades I have shown a cranked bail 280 (Fig. 3) which normally lies idly beneath the depressed blades, but by being given about a quarter 20 turn all such depressed blades are restored to normal idle position where they are held by their spring fingers 263.

By locating the selector pins directly beneath the magazine so that they act on the 25 plate while in the magazine, rather than at some intermediate point in the travel of the plate, I obtain sufficient time after the test of the plate is made by this selector for the paper feed to act. Accordingly I prevent 30 the paper being gripped by the paper feed and started on its course whenever the selective device indicates that it is not desired to print from that plate. This feature of leaving the paper undisturbed when there is to 35 be no imprint made on that cycle of operation is one of the advantageous characteristics of my invention.

Attention is also called to the compactness of my paper feed and selecting mechanism. 40 The selecting mechanism is mounted principally in idle space beneath the bed of the machine, while the paper feed mechanism stands above the machine and requires practically no more lateral space than that required by an addressor where the paper is 45 manually placed in printing position. Furthermore, my paper feed mechanism is adapted to receive sheets fed by any suitable automatic machine, the only requirement being that sheets be supplied one after another 50 against the stop fingers 213 during the time they are elevated.

I claim—

1. In an addressing machine, the combination 55 of a conveyor for address plates, a rotary drum adapted to act as a paper conveyor and having an impression platen, an eccentric mounting for the drum, and means for automatically and periodically turning 60 such eccentric mounting.

2. In an addressing machine, the combination, with a magazine for addressing plates, of a conveyor for moving plates from the 65 magazine, an oscillatory platen adapted to support said plates, a rotary drum adapted

to coact with the oscillatory platen and an interposed address plate, means for feeding paper with the drum into position between it and the address plate, and means for raising and lowering said drum. 70

3. In an addressing machine, the combination with a magazine for addressing plates, a conveyor for the same, a rotary drum carrying an impression platen, belts coacting with the drum to convey paper, an eccentric 75 mounting for the drum, and means for automatically and periodically turning such eccentric mounting.

4. In an addressing machine, the combination with a magazine for address plates, a conveyor for progressing said plates, a rotary drum carrying a platen to coact with a plate, a traveling belt lying in contact with a portion of the surface of the drum and having a portion free from the drum, 80 and means for moving the latter portion into engagement with the paper to feed it to the drum.

5. In a machine of the character described, the combination of a rotary drum, an endless belt lying for a portion of its course in contact with the drum, a movable member carrying a roller over which the belt runs, and means for moving said member to bring 85 a portion of the belt on the roller into contact with the paper to feed the same into the conjoint grip of the belt and drum. 90

6. In a machine of the character described, the combination of a rotary drum, an endless belt in contact with the drum in a portion for the course of the belt, a roller free from the drum about which the belt loops, another roller independent of the belt and adjacent thereto, whereby paper may be 100 placed between the latter roller and belt, and means for causing the belt and said latter roller to pinch the paper between them and thereby feed it. 105

7. In a machine of the character described, the combination of a rotary drum, a belt 110 lying in contact with the drum on one side thereof a roller located in the region on the opposite side of the drum, said belt looping around said roller, a paper table beneath said roller, and another roller beneath the paper table projecting above the top thereof and means for moving the belt down onto the paper. 115

8. In an addressing machine, the combination of a rotary drum carrying a segmental platen, elastic rings around the drum, belts lying in engagement with said rings, and carried by rollers mounted independently of the drum, and means for moving one of 120 said rollers to grip paper and feed it toward the drum. 125

9. In an addressing machine the combination of a rotary drum carrying a segmental impression platen, elastic rings around the drum, belts lying in engagement with said 130

- rings and carried by rollers mounted independently of the drum, a supporting platen, means for feeding address plates between said platens and means for moving the drum toward the supporting platen. 5
10. In a machine of the character described, the combination of a rotary drum, an endless belt having a portion of one reach in contact with the drum, a movable roller carrying a loop of said belt, a paper table mechanism beneath the paper table having suitable fingers adapted to project above it, mechanism for lowering the belt into engagement with the top of the paper on the table and at the same time lowering the fingers from the front of such paper. 15
11. In an addressing machine, the combination with a magazine for address plates, a conveyor for moving plates from the magazine, an oscillatory platen adapted to support said plates, a rotary drum adapted to coact with the oscillatory platen and an interposed address plate, means for raising and lowering said drum, an endless belt in contact with the rear portion of the drum and free from the drum in the upper forward portion, a paper table extending beneath said free forward portion of the belt, and means for controlling the feed of paper along said table into the grip of the belt and drum. 25
12. In an addressing machine the combination with a magazine for addressing plates, a conveyor for plates from the magazine, a platen adapted to support said plates, a rotary drum mounted on an eccentric sleeve, means for turning said sleeve to cause the drum to coact with the supporting platen and an interposed plate, an endless belt in contact with the rear portion of the drum and free from the drum in the upper forward portion, a paper table extending beneath said free forward portion of the belt, and means for lowering the forward portion of the belt to engage paper and feed it along said table into the grip of the belt and drum. 35
13. In an addressing machine the combination with a magazine, a movable supporting platen, a coacting impression platen, means for feeding address plates one after the other from the magazine to a position between the platens, an inking ribbon passing between the address plate and the impression platen, means for reciprocating the ribbon, and mechanism for moving the supporting platen operated by the ribbon reciprocating means. 50
14. In an addressing machine, the combination of a magazine for address plates, an oscillatory supporting platen, a coacting impression platen, a means for feeding plates one after the other from the magazine to a position between the platens, a reciproca-
- tory inking frame, and mechanism connecting it with the oscillatory platen. 65
15. In an addressing machine, the combination with a magazine, an oscillatory platen, a coacting impression platen, means for feeding the plates one after the other from the magazine to a position between the platens, an inking ribbon passing between the plate and impression platen, a reciprocatory frame carrying said ribbon, a rack on said frame, a gear member meshing with the rack, and a connection between the same and the supporting platen. 70
16. In an addressing machine the combination of a magazine for address plates, an oscillatory supporting platen, an impression platen above the supporting platen, a pair of conveyor chains adapted to feed plates one after the other to a position between the platens, a reciprocatory inking frame, a rack carried thereby, a tooth sector meshing with the rack and a link connecting said sector with an arm of the oscillatory platen. 80
17. In an addressing machine, the combination with a magazine for addressing plates, an impression platen, a conveyor adapted to convey plates from the magazine into position to coact with the platen, means for periodically moving the platen to idle and active position, and a selecting device coacting with the bottommost plate in the magazine and controlled by such plate for determining whether the platen shall come to active position to print from that plate. 90
18. In an addressing machine the combination with a magazine for addressing plates, an impression platen, a conveyor adapted to convey plates from the magazine into position to coact with the platen, means for feeding material to be impressed, and a selecting device controlled by the plates for determining whether the material shall be fed. 100
19. In an addressing machine, the combination with a series of address plates, projecting tabs separable from the plates, means on each plate for holding the tab in any one of several positions thereon, of mechanism adapted to be engaged differently by the tabs in different positions and including a series of abutments adapted to be set, means for printing from the address plates, and means whereby said mechanism controls the printing, but causing said abutments to intercept or clear means effecting the impression. 110
20. The combination with a series of address plates having differently positioned index tabs thereon, a magazine for holding such address plates, means for progressing such address plates, means for feeding paper thereto, and mechanism whereby the tabs may control the paper feed. 125
21. In an addressing machine the com-

bination with a magazine adapted to hold a series of address plates with index tabs adapted to be variously positioned, a series of members adapted to be engaged respectively by the tabs in different positions, means for feeding paper to the address plates, and means whereby said members control the feeding.

22. The combination with a series of address plates, projecting tabs separable from the plates, means on each plate for holding the tabs in any one of several positions thereon, a magazine for holding such address plates, means for feeding such address plates, means for printing therefrom, a series of movable abutments corresponding to different positions of the tabs and adapted to engage the bottommost plate in the magazine, mechanism whereby the tabs cause movement of the abutments, and mechanism for affecting the printing having a movable member and whose path of movement may be intercepted by any of said abutments.

23. The combination with a series of address plates, projecting tabs separable from the plates, and means on each plate for holding the tab in any one of various positions thereon, of mechanism for holding such plates, a series of members adapted to be selectively engaged by the tabs, a rotary impression platen, a conveyor for carrying the plates into position to coat with the platen, means for moving said platen to and from active position, and mechanism actuated by a selected member for controlling said means.

24. The combination with a series of address plates having index tabs differently positioned on different plates, mechanisms for holding such plates, a series of members adapted to be selectively engaged by the tabs, a conveyor for progressing the plates, means for moving paper into position to be impressed by the plate, and mechanism actuated by a selected member for controlling said means.

25. The combination with a series of address plates, projecting tabs separable from the plates, and means on each plate for holding the tab in any one of various positions thereon, of a stationary series of pins corresponding to the respective positions of the tabs, each pin being adapted to be actuated by a tab juxtaposed therewith, and means for controlling the printing actuated by said pins.

26. The combination with a series of address plates, projecting tabs separable from the plates, and means on the plate for holding the tab in any one of various positions thereon, of a series of pins corresponding to the respective positions of the tab, each pin being adapted to be actuated by a tab juxtaposed therewith, a series of abutments corresponding to the pins and movable respectively thereby, said abutments being adapted

to be positioned in the path of mechanism whose movement is necessary for printing and be removed from such path by the actuation of said pins.

27. In an addressing machine, the combination with address plates having index tabs differently positioned on different plates, a magazine for such address plates, a row of pins extending across the magazine, a series of abutments operated by the respective pins, impressing mechanism, means for moving the same to active position including a member having a path of movement which may be intercepted by any one of said abutments.

28. In an addressing machine, the combination with address plates having index tabs differently positioned on different plates, a magazine for such address plates, a row of pins extending across the magazine, a series of abutments operated by the respective pins, and paper feeding mechanism some part of which has a path of movement which may be intercepted by any one of said abutments.

29. In an addressing machine, the combination of a magazine for address plates, a series of pins beneath the same, a series of pivoted blades beneath the pins and adapted to be moved by the depression of the pins, a universal member movable in a path which intercepts any blade when its pin is in raised position, but clears that blade when its pin has been lowered, an impression platen having an eccentric mounting, and a connecting mechanism between said universal member and said eccentric mounting.

30. In an addressing machine, the combination of a magazine for address plates, a series of pins beneath the same, a series of pivoted blades beneath the pins and adapted to be moved by the impression of the pins, a universal member movable in a path which intercepts any abutment when its pin is in raised position, but clears that blade when its pin has been lowered, and paper feed mechanism controlled by said universal member.

31. In an addressing machine the combination with a magazine for address plates and a series of movable pins extending across the magazine, a corresponding series of pivoted blades movable by said pins, a universal abutment member adapted to move in a path which intersects an idle position of said blades, but is free therefrom when the blades have been swung on their pivots by movement of said pins, and means controlled by said universal abutment member and in turn controlling some necessary factor in printing on paper.

32. In an addressing machine, the combination with a magazine for address plates and a series of movable pins extending across the magazine, a corresponding series of pivoted blades movable by said pins, a uni-

versal abutment member adapted to move in a path which intersects an idle position of said blades, but is free therefrom when the blades have been swung on their pivots by

5 movement of said pins, a rotary impression platen, an eccentric mounting therefor, connecting mechanism between said abutment member and said eccentric mounting and conveyor chains adapted to convey the bottommost plate in the magazine into position for coaction with said platen.

33. In an addressing machine, the combination of a magazine for a stack of address plates, an endless conveyor for feeding the bottommost plate forwardly, a supporting platen for such plate, a rotary paper feeding drum having an impression platen above the supporting platen, means for feeding paper onto the upper surface of said drum, 20 means for guiding such paper about the drum to cause it to pass between the drum and the address plate, mechanism for conjointly controlling the paper feed and the presentation of the impression platen to the address plate, and a selection device whereby said mechanism is controlled by suitable characteristics on the plates.

34. In an addressing machine, the combination of a magazine for address plates, a 30 supporting platen, means for feeding the bottommost plates from the magazine into position over the platen, a reciprocatory ribbon frame overlying such platen, an impression platen, a paper feeding drum over the ribbon and carrying the impression platen to coact with the ribbon and a plate, and a selective device controlled by plate characteristics for shifting the axis of the drum.

40 35. In an addressing machine, the combination of a magazine for address plates, a stock of address plates in such magazine some of which have tabs projecting from an edge of the plate, and a selecting device 45 having a stationary series of movable members acting on the tabs on the endmost plate while it is in the magazine.

36. In an addressing machine, the combination of a magazine for address plates, 50 there being space within the magazine for tabs on the edge of the address plates, a stack of address plates in such magazine

some of which have tabs projecting beyond an edge of the plate, and a selecting device located at least in part below the magazine and having members adapted to be engaged by tabs on the plates as they come to the bottom of the magazine.

37. In an addressing machine, the combination with a magazine for address plates, 55 means for feeding the bottommost plate and for feeding paper to an impressing couple for printing from such plate, of a selecting device to control the printing, said selecting device having a series of members adapted to engage tabs in various positions on the address plates as they successively become the bottommost plate in the magazine, each member being adapted to prevent the printing operation and prevent the feeding 70 of paper, whereby said members may be used either singly, each by one tab, or in combinations by a plurality of tabs on a given plate.

38. In an addressing machine, the combination of a magazine for address plates, a supporting platen, means for feeding the bottommost plates from the magazine into position over the platen, a reciprocatory ribbon frame overlying such plate and 80 platen, a paper feeding drum over the ribbon and carrying an impression platen adapted to coact with the ribbon and a plate, a discharge guide for paper lying above the ribbon and terminating close to 85 it, and ejector rollers coacting with the drum.

39. In an addressing machine the combination of a magazine for address plates, a supporting platen, means for feeding the 90 bottommost plates from the magazine into position over the platen, a reciprocatory ribbon frame overlying such plate and platen, a paper feeding drum over the ribbon and carrying an impression platen adapted to coact with the ribbon and a plate, and endless 95 belts engaging the rear face of the drum, and adjustable means for timing the feed of paper into the space between such belts and drum.

100 In testimony whereof, I hereunto affix my signature.

LAWRENCE H. MORSE.
